MACHINE AND METHOD FOR FOLDING BOX BLANKS

Leon E. La Bombard, Nashua, N. H., assignor to International Paper Box Machine Company, Nashua, N. H., a corporation of New Hampshire

Application March 18, 1952, Serial No. 277,242

10 19 Claims. (Cl. 93—49)

This invention relates to an improved method and apparatus for infolding the leading or trailing flaps of a flat box blank as the blank travels along the paper line of a box folding machine. It is particularly useful in folding blanks having a large number of leading flaps each of considerable length longitudinally such as are found on the "Himes" type box, well known in the trade. Instead of one or two comparatively short and wide leading flaps, boxes of the "Himes" type present four long, narrow flaps which are difficult to infold on high speed machinery. Furthermore two of the leading flaps on such boxes are usually wide and include a diagonally articulated sealing tab to be bent in a direction opposite to infolding, while being infolded, and therefore have different folding characteristics from the other two narrower flaps.

Various methods have heretofore been proposed for infolding the leading flaps of a box blank for example the prebreaking of all flaps upwardly, at one station on the paper line, and the infolding of such upwardly bent flaps, at a second station on the paper line, by placing a stationary obstruction in their path, above the paper line. My invention eliminates the preliminary upfolding station and its mechanism and folds each flap from a flatwise position in extension of the blank to an infolded position all at the same station on the paper line. In my device one or more of the leading flaps of the same type are completely infolded at a first station, while the remaining flaps are held down on the paper line. The remaining flaps of another type are completely infolded at a second station, while the first infolded flaps are in turn held down on the paper line.

Methods have previously been proposed for infolding a flat leading flap at a single station. One such method comprises the use of a fixed, upstanding, spring on the paper line arranged to exert pressure from underneath the flap to lift it into contact with a fixed obstruction positioned above the paper line. Another such method has been the use of an arm, pivoted below the paper line, which advances with the blank as it pivots to fold the flap. Another such method includes the use of an arm, pivoted at a fixed position above the paper line, which kicks the flap upwardly from a pivot point in advance of the flap. The devices used in such methods have certain disadvantages in that a spring is impositive and may wear out, a stationary pivoted arm may fracture the flap at high speeds and an arm pivoted below the paper line but advancing with the blank, involves considerable mechanism to hold the blank down during folding.

One object of my invention is to provide means for infolding a leading or trailing flap of a flat box blank, as it travels along the paper line of a folding machine, without the necessity of a separate station for pre-breaking and pre-bending such flaps upwardly. A further object of my invention is to infold all leading flaps of one type at one station and all those of another type at another station, and/or to similarly infold the trailing flaps, the infolding mechanism at each station being positive at

2

high speeds and having no complicated mechanical linkage between the flap upfolding and blank hold-down mechanism.

Another object of my invention is to provide a rigid guide for applying a gradually increasing upward pressure under the leading edge of each leading flap or the trailing edge of each trailing flap as it moves along the paper line thus urging the flap to bow and then to bend at its line of articulation, combined with an efficient hold down member applied to the part of the blank to which the flap is articulated. Still another object of my invention is to provide a member pivotally mounted above the paper line and provided with a longitudinally extending surface, which surface moves from a flatwise position beneath one portion of the paper line to an inclined position above another further advanced portion of the paper line thereby upfolding each leading or trailing flap accurately into engagement with a stationary back-folding member. Another object of my invention is to associate with such a pivotally mounted member, a similarly pivoted hold-down arm for use in holding down the adjacent portions of blanks of less bendable material.

In the drawings,

Fig. 1 is a side elevation partly in section of a folding machine constructed in accordance with my invention to fold the leading flaps of an advancing blank.

Fig. 2 is a plan view of the folding machine illustrated in Fig. 1.

Figs. 3—7 are each enlarged side elevations of my new pivoted flap-uplifting and blank hold-down mechanism and my stationary infolding member in various stages of infolding a leading flap of an advancing blank.

Figs. 8—10 are each enlarged side elevations of my new pivoted flap-uplifting mechanism and my stationary infolding member in various stages of infolding a leading flap of an advancing blank of material not requiring any blank hold-down mechanism.

Fig. 11 is an enlarged side elevation showing my invention in combination with a folding bar arranged to back fold a diagonally articulated tab on the flap.

Fig. 12 is an enlarged view of the blank shown in Fig. 2.

Fig. 13 is a view of an erected box made from the blank shown in the drawing.

Fig. 14 is a fragmentary side elevation partly in section of a folding machine constructed in accordance with my invention to fold the trailing flaps of an advancing blank.

Figs. 15—18 are each enlarged fragmentary side elevations of the folding mechanism of Fig. 14 in various stages of infolding a trailing flap of an advancing blank.

Fig. 19 is a fragmentary rear view of the pivot portion of the mechanism shown in Figs. 14—18.

As shown in Figs. 12 and 13, A represents one form of blank for which my invention is especially adapted, namely a blank of the "Himes" type, although it should be noted that my folding mechanism and method is useful in folding the leading or trailing flaps of blanks of many other types. Blank A has two end wall panels 20 and 22, two side wall panels 21 and 23 and a wall sealing tab 24, which is articulated to side wall panel 23. It is also provided with cover panels 25, 26 and 27 connected to side panels 20, 21 and 22 on a line of articulation 28 which may be creased or scored. Two identical bottom sealing flaps 30 and 32 and two identical bottom locking flaps 31 and 33 are connected to the side panels 20, 21, 22 and 23 on a line of articulation 38 which also may be creased or scored. Each flap 30, 31, 32 and 33 is of the same width as the side panel to which it is connected, but is of greater length, and flaps 31 and 33 are of greater width than flaps 30 and 32. A bottom sealing tab 34 is formed in flap 31 by a diagonal line of articulation 37 and a bottom sealing tab 35 is formed in flap 33.

by a diagonal line of articulation 36. Suitable slits, cut-outs and lines of articulation, well known in the trade, are also formed in blank A, as shown in Figs. 1 and 2 whereby the blank can be formed into the collapsed box shown in Fig. 13 with the bottom flaps folded between the wall panels and ready to automatically fold downwardly to form a bottom for the box when erected, as shown in Fig. 13.

Box blanks such as A are advanced along the paper line P of my folding machine in a flatwise, horizontal position with the flaps 30, 31, 32 and 33 leading the blank and with the lines of articulation 28 and 38 transverse to the direction of travel of the blank. The principal purpose of my folding machine is to infold leading flaps such as 30, 31, 32 and 33 of a blank such as A on their line of articulation 38 to overlie the side wall panels 20, 21, 22 and 23 and to back fold tabs 34 and 35 on diagonal lines of articulation 36 and 37 so that the blank assumes the form shown at B in Fig. 2.

My folding machine includes a frame C having suitable supports 40, 40 and having upstanding side plates 41, 42 which extend longitudinally thereof. All of the feeding, folding and gluing mechanism of my machine is slidably mounted on rods, or shafts, extending between side plates such as 41 and 42 so that all of the parts can be fixed in the correct transverse position to accommodate blanks of different sizes and shapes. Similarly all of the rotating members of my machine are connected by suitable gears, belts or chains so that they operate in synchronization and are suitably powered from a source not shown in a manner not shown in detail since it is well known in the trade.

I provide a plurality of parallel, endless conveyors such as D, which may be belts or chains, and each of which includes upstanding lugs 45, at spaced intervals therearound, arranged to receive and advance a blank along the paper line P formed by the upper stretch of the conveyors. Each conveyor D, extends substantially the full length of my machine, between the feeding mechanism E and the gluing mechanism G, and is trained around pulleys 43 mounted on a longitudinally extending support 44 which, in turn, is slidably transversely on rods or shafts 46. Each conveyor D, with its support 44 and pulleys 43, can thus be moved transversely of the machine to position it under a particular flap such as 30, 31, 32 and 33 and thus to support and advance a blank such as A through the folding mechanism F without interfering with the revolving folding members which extend below the paper line P.

Feeding mechanism E may be of any well known construction and as illustrated herein, includes a plurality of feeding rolls 54, each slidably mounted on a powered shaft 52 and a hopper or trough 50 for a stack of blanks such as A. Feeding rolls 54 are arranged to feed blanks one at a time from the stack onto conveyors D where they are engaged by lugs 45 and advanced through the folding mechanism F and gluing mechanism G in timed and spaced relation thereto.

Gluing mechanism G may also be of any well known construction and as illustrated herein, includes a plurality of glue rolls 64, each slidably mounted on a powered shaft 62 and having suitable glue supply rolls and pots indicated at 60. Glue rolls 64 are arranged to deposit a triangular patch of adhesive on the back turned bottom sealing tabs 34 and 35 of a blank such as B so that they can be adhesively secured to the bottom sealing flaps 30 and 32 as shown in Figs. 12 and 13.

A pair of oppositely disposed pressure rolls 70 and 71, each extending the full width of the machine, between side plates 40 and 41 are provided to iron out the folds created by folding mechanism F prior to arrival at the gluing mechanism G.

Folding mechanism F is the essence of this invention and as explained above, the folding operation preferably takes place at two stations indicated at 100 and 200. At station 100 the first station, the flat leading flaps 30 and

32 of a blank such as A are bent upwardly and then backwardly on the line of articulation 38 into infolded position overlying side wall panels 20 and 22 as shown at B.

For convenience the bottom sealing tabs 34 and 35 are pre-broken downwardly on lines of articulation 37 and 36 also at this station. At station 200, the second station, the flat leading flaps 31 and 33 of a blank such as A are bent upwardly and then backwardly on the line of articulation 38 into infolded position overlying side wall panels 21 and 23 as shown also at B. The folding of the pre-broken bottom sealing tabs 34 and 35, in a direction opposite to the direction of folding of flaps 31 and 33, commences at station 200 and is completed 15 shortly after the completion of the infolding of flaps 31 and 33.

At the first station 100, I provide a pair of endless hold-down chains 101, 102 each chain such as 101 being carried on sprockets such as 103 on transverse shafts 104 and 105. Chains 101 and 102 are each aligned above one of the endless conveyors D and each is adjustable to various transverse positions in the same manner as is each conveyor D. Leading flap 31, side wall panel 21 and cover panel 26 are thus advanced through station 100 by a lug 45 of a conveyor D, while supported from below by the conveyor and held down on the paper line P by hold down chain 101. Leading flaps 30 and 32 are supported from below by other conveyors such as D but since there is no hold down chain above these flaps, at station 100, space is available above the paper line P for folding mechanism to be described hereinafter.

As shown in Figs. 1 and 2 and somewhat diagrammatically in Figs. 3-7, my folding mechanism includes a rigid arm 110, bent at 111 to form an elongated flap-uplifting finger 112. Arm 110 is rotatably mounted at 151 on a powered shaft 113, to revolve on an axis above and transverse to the paper line P and in a vertical plane perpendicular to the plane of said paper line. Finger 112 has a rigid plane, straight face or surface 114, which is preferably nearly as long as the flap 30 to be folded thereby and as shown in Fig. 3, when arm 110 is in the rotational position shown, rigid plane surface 114 is parallel with and just below the paper line P. Arm 110, finger 112 and the rigid plane surface 114 all describe a circular path around the shaft 113, located above the paper line P, the portion of the path proximate the paper line being in the same direction as the path of the blanks on the paper line as indicated by the arrows, but the rate of advance being less than that of the blanks. I prefer to use two oppositely disposed arms 110, each having a flap uplifting finger 112 and each finger being timed and spaced to uplift a leading flap of a blank advancing on the paper line, although it is obvious that more or less arms can be used as desired.

In Fig. 3 I show a blank such as A with a leading flap 30, side wall panel 20 and cover panel 25 all in flatwise condition on paper line P and being advanced therealong in the direction of the arrows. Conveyors D and hold down chain 101 are merely indicated since at this first station 100, they are engaging panels and flaps which will not be folded and are clearly shown in Figs. 1 and 2.

The rigid, plane flat, straight surface 114 of flap uplifting finger 112 is substantially horizontal, just below the paper line P, so that the undersurface of the leading edge of leading flap 30, at 39, overlies the trailing portion of surface 114 at 115. My stationary infolding means is included in my folding mechanism and comprises an elongated member 130 fixed at a predetermined height above paper line P and having a notch 131 shaped and positioned to receive the leading edge of an upturned flap such as 30 and having a downwardly tapered undersurface at 132 and 133 shaped and positioned to bend the flap downwardly as the blank such as A advances thereunder on the paper line. A flap such as 30, which has been guided upwardly into notch 131 will thus be overfolded or infolded on its transverse line of articulation to

overlie its side wall panel such as 20 when it has been advanced to the end 134 of member 130. The first folding station thus extends from the point on the paper line at which the undersurface of flap 30 is contacted by the rigid plane surface 114 of finger 112, shown in Fig. 3 to that point on the paper line under the end 134 of the stationary infolding member 130.

Also included in my folding mechanism is a rigid hold-down arm 150, rotatably mounted at 151 on powered shaft 113 to revolve with arm 110 on the same axis and in the same plane relative to the paper line P. Each arm 150 may be fixed in a predetermined angular position relative to the arm 110, with which it cooperates, by a set screw 152, and if not needed due to the characteristics of the paperboard of the blank, or the conformation of the leading flaps of the blanks it may be revolved flush with arm 110 as shown in Figs. 8-11. As shown in Figs. 3-7, however arm 150 is adjusted to follow arm 110 so that the tip 154 of arm 150 will contact the upper surface of the panel 20 to which the leading flap 30 is articulated, just behind the line of articulation 38 while arm 110 is uplifting flap 30.

In Fig. 4, the blank A is shown in an advanced position on paper line P and arms 110 and 150 are also shown in advanced positions on their respective circular paths. However, since arms 110 and 150 advance at a less rate of speed than the blank A, the undersurface 39 of the leading flap 30 has slid up the rigid plane surface 114 of the gradually inclining flap-uplifting finger 112. At this point the blank A is being held down on the paper line P by hold-down chains 101 and 102 which are laterally spaced from flaps 30 and the tip 154 of hold-down arm 150 has not yet contacted the upper surface of panel 20 so that the flap 30 and panel 20 may be inclined or bowed upwardly as indicated in Fig. 4.

In Fig. 5 the blank A is shown in a still further advanced position on the paper line P and arms 110 and 150 are correspondingly advanced in their circular paths. The less rate of advance of arm 110 has caused the undersurface 39 of flap 30 to slide still further up the rigid plane surface 114 of finger 112 and the tip 154 of arm 150 has contacted the upper surface of panel 20. If flap 30 had not already become upfolded on its line of articulation 38 by the lifting action of the rigid plane surface 114, the downward pressure of the tip 154 on panel 20 will cause the flap to bend positively at the line 38.

In Fig. 6 the blank A has continued to advance along the paper line P and the rigid plane surface 114 of finger 112 has positively and accurately guided the leading edge of flap 30 into the notch 131 of the stationary infolding member 130. At the same time the finger 112 and the tip 154 of arm 150 have completed their upfolding function and are revolving out of the way.

In Fig. 7 the flap has continued to advance along the paper line P under the stationary infolding member 130 and the flap 30 is being gradually bent downwardly on its line of articulation 38 to overlie panel 20 by the undersurface 133 of member 130. Uplifting finger 112 and hold-down arm 150 have also advanced in their circular paths which carry them around centre of rotation 113 for a complete revolution to repeat the operation on the leading flap of a succeeding blank.

Each stationary infolding member 130 is fixed at the lower end 136 of an arcuate member 137 and the upper end of member 137 is slidably mounted in a bracket 138 by means of set screws 135. The arc of member 137 is concentric with the circular path of finger 112 and hold-down arm 110, so that if a flap of greater or lesser length is used on a blank such as A, it is only necessary to slide the arcuate member 137 upward or downward to the desired position in bracket 138. Each bracket 138 is slideable transversely on a rod 139 and each arm 110 and 150 is also slideable transversely on shaft 113 to assume various positions in accordance with the location of the leading flaps on the blanks to be infolded.

I find it convenient to locate tab pre-breaking mechanism H at the first station, as shown in Figs. 1 and 2, because the leading flaps 31 and 33 to which the bottom sealing tabs 34 and 35 are articulated are firmly held beneath conveyors D and hold-down chains 101, 102 at this station. I provide an endless chain 170, having outwardly projecting lugs 171 therearound, each arranged to contact a tab such as 34 and bend it downwardly below the paper line P thus pre-breaking it on its line of articulation 37. Chain 170 is trained around sprockets 172, 173, journalled in a rigid support 174, which support depends from a transverse rod 175 and is slidably adjustable in various positions thereon by a set screw 176. Beneath the paper line P, under and diagonal to the path of lugs 171 of chain 170 I may place tab folding guides 177 to assist in prebreaking each tab such as 34.

After leading flaps such as 30 and 32 have been infolded and tabs such as 34 and 35 have been pre-broken at the first station 100, the blank A passes out from under hold-down chains 101 and 102 and while still being advanced by conveyors D, passes under a second pair of hold-down chains 201, 202. Hold-down chains 201 and 202 are in line with two infolded leading flaps 30 and 32 and serve to keep such flaps infolded as well as to hold the blank down on the paper line P at the second folding station 200. Each hold-down chain, such as 201, is carried on sprockets such as 203 on transverse shafts 204 and 205, and is powered and adjusted in a manner similar to that of chains 101, 102.

As shown in Figs. 8-11, at the second station 200, I provide a rotating uplifting finger 212 for each flap such as 31 or 33 to be infolded at that station. I prefer to also use a rotating hold-down arm such as 150 with each finger 112 or 212 at each station, but since my rotating uplifting finger will lift and upfold flaps successfully without an arm such as 150 on very bendable material I have illustrated the action thereof in Figs. 8-11.

As shown in Fig. 8 a leading flap 33 of a blank such as A, with its bottom sealing tap 35 pre-broken downwardly contacts the rigid plane straight surface 214 of the elongated flap uplifting finger 212 with the undersurface 239 of the flap and it should be noted that surface 214 is substantially co-extensive in length with flap 33. In Fig. 9 the blank A has advanced along the paper line P so that flap 33 has slid upward along the surface 214 which is advancing at a less rate of speed than the blank but in the same direction. In Fig. 10 the blank has advanced still further along the paper line and the flap 33 has slid still further along the gradually inclining and rising surface 214 until the flap folds upwardly on its line of articulation 38. In Fig. 11 I show the blank further advanced on the paper line P, the finger 212 releasing the flap 33 into the notch 231 of a stationary infolding member 230 which is identical with member 130. Bottom sealing tab 35 is shown being slidably engaged by a folding guide 260 which extends longitudinally of the paper line in a well known manner to backfold the tab 35 as the flap 33 is infolded by undersurface 232 and 233 of member 230 to overlie side wall panel 23. Guides 260 are mounted for lateral movement by means of a bracket 360, slideable on a transverse rod 361.

While my invention is especially useful for infolding the leading flaps of blanks advancing along a paper line, as shown in Figs. 14 to 19 it may also be used to infold the trailing flaps of such blanks. For example to infold a single trailing flap such as 26, or a pair of similar trailing flaps such as 25 and 27, of a blank such as A, I provide a folding mechanism M on frame C in place of folding mechanism F or in advance thereof. Preferably the infolding of different types of trailing flaps takes place at different stations but for illustration I show only one such station 500 in Figs. 14 to 19. It will be understood that pre-breaking mechanism such as H, hold-down chains such as 101, 102, 201 and 202 and folding

guides such as 177 and 260, similar to those shown in Figs. 1-13, are also used where required.

As shown in Fig. 14, I provide two transverse shafts 501 and 502 extending between upstanding side plates such as 41 and 42 of frame C, upon which my folding mechanism M is mounted, mechanism M being above conveyor D and paper line P. One or more rigid members 503 are slidable transversely on shafts 501 and 502, each movable into position above a particular flap of a blank such as N carried by conveyor D. A sprocket 506 is journaled at 507 at one end of member 503 and a similar sprocket 508 is journaled at 509 to the opposite end thereof. A chain 510 is trained around sprockets 506 and 508 and is suitably connected to the power train of the machine to enable the lower stretch 511 of the chain to advance in the direction of travel of blank N but at a greater rate of advance than said blank.

Spaced along chain 510 are links such as 513 to each of which a rigid arm 514, similar to arm 110, is pivotally mounted on a pivot pin 515. Each arm 514 is bent at 516 to form an elongated, flap-uplifting finger 517 having a rigid flat, straight, plane surface 518. Each arm 514 is further provided with an extension 520 carrying a roller cam follower 521, the cam follower being in rolling contact with an elongated downwardly inclined cam track 550 which extends along the lower stretch 511 of chain 510. Cam track 550 is fixed to member 503 and is so shaped and positioned as to cause follower 521 to rotate the rigid plane surface 518 of arm 514 from a position below and parallel to paper line P to a gradually increasing angle of elevation to the paper line as the arm 514 advances along the lower stretch 511.

Links 574, 575 of chain 510, located in front and in rear of link 513, are provided with transversely extending abutments, such as elongated pins 522, 523, for engagement with ears 524, 525 of arm 514. Ear 524 is an anchor for a coil spring 526, the spring 526 being arranged to urge the arm 514 in a counterclockwise direction. Ear 525 is a stop member to prevent the movement of the arm 514 beyond the position shown in Fig. 15. Thus the arm 514, after performing its folding operation along the lower stretch 511 of chain 510, is returned to its normal position by return spring 526 when it reaches the end of the curved portion 551 of cam track 550 and the arm is then ready to again perform its function on a succeeding blank.

A blank hold-down arm 630 similar to arm 150 is pivotally mounted on pivot pin 515 of a link such as 513 and may be fixed in various angular positions relative to arm 514 by means of a slot 631 and a set screw 632. Located at station 500, and also included in folding mechanism M, is a stationary infolding means comprising an elongated member 630 fixed at a predetermined height above the paper line P. Member 630 is similar to member 130 of folding mechanism F except that no notch such as 131 is necessary, and member 130 is provided with a downwardly tapered undersurface at 633 shaped and positioned to bend a trailing flap downwardly as the blank advances thereunder. Member 630 is fixed at the lower end 636 of an arcuate member 637 while the upper end of member 637 is slidably mounted in a bracket 638 by means of set screws. Bracket 638 is slidable transversely on shaft 502 whereby the stationary infolding member 630 can be positioned in various transverse positions and at various height and angles with relation to paper line P.

As shown in Fig. 15, a flat blank N is advanced along paper line P by the conveyor D, and held down by hold-down chains such as 101, not shown. At station 500 an arm such as 514, traveling at greater speed than blank N, moves into the position shown. The rigid plane surface 518 of flap uplifting finger 517 is parallel to the paper line P and extends under the trailing edge of the trailing flap, such as 700 of blank N. In Fig. 16, the surface 518 is shown extending further under flap 700

as the flap uplifting finger 517 gradually assures an increased angle of elevation to the paper line P due to the clockwise pivoting of arm 514 caused by cam track 550. Hold-down finger 650 has pivoted with arm 514 and at this point is in contact with the panel 701 to which flap 700 is articulated just behind the line of articulation 702.

As indicated in dotted lines in Fig. 14, flap 700 is up-folded by surface 518 of arm 514 until it folds on the line 702 and until it engages the stationary infolding member 630 the arms 514 and 650 then being raised out of the way and the tapered undersurface 633 continuing the infolding of the flap as illustrated in Figs. 17 and 18. At the terminal point 639 of member 630 which is also the terminal point of station 500 the flap passes under a hold-down bar 690 of a well known type which maintains the flap in infolded position as it continues along the paper line P.

It will be apparent that my method of infolding a leading or trailing flap of a flat box blank at a single station by positioning a rigid plane surface at the paper line which slides the flap upwardly into positive and accurate engagement with a stationary infolding member is especially suitable for high speed production of folded paper boxes. Since the flaps are supported and guided throughout the infolding operation by rigid plane surfaces, rather than springs or kicking levers, there is no possibility of rupture of the blank or failure to fold properly at the desired line of articulation.

It will also be apparent that I can backfold a sealing tab such as 35, while the flap to which it is articulated is flat, by pre-breaking the tab downwardly into the path of a backfolding guide such as 260 positioned under the paper line. Similarly, I can backfold such a tab, while the flap to which it is articulated is being unfolded, by positioning a backfolding guide, such as 260, above the paper line.

My device is particularly useful with paperboard box blanks but is also useful for the blanks of other containers such as envelopes.

I claim:

1. In a machine for use in making knockdown boxes, means for continuously advancing a box blank at a predetermined speed along a paper line with the line of articulation of the blank flaps transverse, and the line of articulation of the blank tabs diagonal, to the direction of advancement of said blank; stationary infolding means positioned above said paper line; a notch in said stationary infolding means positioned to form a pivot for the leading edge of an upwardly lifted flap of said advancing blank and adapted to infold said flap against the main body thereof on its transverse line of articulation as said blank advances thereunder; leading flap uplifting mechanism, including a rigid, plane, longitudinally extending surface positioned to slidably contact the undersurface of the leading edge portion of a flat flap of said blank, at the paper line; means, synchronized with said blank advancing means, for advancing said surface in the direction of travel of said blanks while increasingly inclining said surface, thereby guiding the leading edge of each successive leading flap upwardly above the paper line into engagement in the notch of said stationary infolding means; and a stationary longitudinally extending folder bar positioned above the path of a triangular tab, adjacent said infolding means and uplifting mechanism, said folder bar being arranged to fold said tab in the opposite direction to that of said infolded leading flap.

2. A device for use in upfolding the transversely articulated flaps of a flat box blank advancing along a paper line of a folding machine, said device comprising an arm mounted to rotate in a vertical plane around a transversely extending axis of rotation above the paper line, a flap-uplifting finger carried by said arm, said finger extending longitudinally under, and substantially parallel to, said paper line for engagement with the under sur-

face of the edge portion of a transversely articulated flap and being movable, by the rotation of said arm, to advance with said blank while assuming a gradually increasing angle of inclination to the paper line, and a holdown arm, fixed at a predetermined angular relation to said uplifting finger and mounted to rotate in a vertical plane around said axis of rotation, said holdown arm being arranged to press the main body of the blank down on the paper line after said flap is guided upwardly by said uplifting finger, thereby positively causing a fold at the line of flap articulation.

3. In a machine for use in making knockdown boxes; timed means for continuously advancing a flat box blank at a predetermined speed along a straight, horizontal path through said machine with the lines of articulation of the longitudinally extending flaps thereof transverse to said blank path; a folding arm of rigid material, operable at a folding station along said blank path, said arm being angularly bent at one end to form a hook with an elongated straight plane inside face for slidably engaging a flap; timed means supporting the other end of said arm and moving the same continuously and unidirectionally in an endless, closed path above said blank path, said arm supporting means and arm being arranged to initially position the inside face of said hook under and parallel to the outer edge portion of a longitudinally extending flap of each successive blank advancing along said blank path and to advance with said flap along said path at a different rate of speed than that of the blank while sliding further under said flap and uplifting the same on its transverse line of articulation and a stationary flap infolding member mounted above said blank path at said folding station, said member receiving each successive uplifted flap from the hook of said arm and infolding the said flaps flatwise against the blank as the blank continues advancing thereunder.

4. In a folding machine, mechanism for folding the leading flaps of flat articles, said mechanism comprising timed means for advancing a plurality of flat articles individually and successively along a straight path through said machine with the lines of articulation of the leading flaps thereof transverse to said blank path; a rotatable, angularly hooked folding arm of rigid material mounted to rotate around a laterally extending axis of rotation above said blank path in a vertical plane longitudinally of said path, the hook portion of said arm trailing rearwardly thereof and being substantially co-extensive in length with the length of a flap to be folded thereby and having a straight, flat, plane inside face for slidably engaging the under face of a flap and the shank of said arm being of greater length than the distance from said centre of rotation to the said blank path to position its trailing hook portion flatwise in supporting position under an advancing flap once during each revolution thereof and timed means, synchronized with said blank advancing means, and rotating said hooked arm in a closed, unidirectional, circular path, said means being adapted to present the straight flat face of said hook initially horizontally under each successive leading flap, to then advance and angularly incline said face while causing the flap to slide further along the face and be uplifted on its line of articulation and to then rotate said face through a complete reevolution back to its initial position.

5. A folding machine as specified in claim 4 plus a stationary, overfolding member fixed above the path of said blanks and in the path of a flap uplifted by the hook of said folding arm, said member having a rearward facing notch in the rearward edge thereof arranged to receive the leading edge of each successive uplifted leading flap and serve as a pivot point for forcing the said flap

5
10

to fold on its line of articulation before being overfolded by said member.

6. A folding machine as specified in claim 4 plus a blank holdown arm rotatable with said folding arm around said centre of rotation but angularly spaced therebehind to press downwardly on the upper face of a blank behind the line of articulation of a leading flap after said hook has engaged and uplifted said flap thereby assisting in causing the flap to fold on its correct line of articulation.

7. A folding machine as specified in claim 5 wherein said stationary overfolding member is mounted on said machine for slidable adjustment on an arcuate member, the centre of the arc of said member being at the centre of rotation of said hooked folding arm.

8. Apparatus for upfolding the leading flaps of flat foldable articles, said apparatus comprising timed means for advancing a plurality of flat foldable articles individually and successively along a straight path with the line of fold of the leading flaps transverse to said path; a rotatable support mounted for rotation in a vertical longitudinal plane on an axis of rotation transverse to and above said path; at least one straight, flat, folding finger of rigid material carried by, and rotatable with said support, said finger being adapted to move from a position flatwise under and parallel to said article path to a position further advanced therealong, perpendicular to, and above, said path with each complete revolution of said rotatable support and timed means, synchronized with said article advancing means, for continuously and unidirectionally revolving said rotatable support with the horizontal component of advance of said finger, between the said positions, being at a predetermined less rate than the rate of advance of said articles whereby a leading flap slides along said finger as it is upfolded on its line of articulation.

9. Apparatus as specified in claim 8 wherein said straight flat finger is substantially co-extensive in length with the length of a flap to be upfolded thereby.

10. A rotary method for upfolding the longitudinally extending flaps of a plurality of flat box blanks advancing individually and successively along a longitudinal path at a predetermined rate of advance, said method comprising the steps of applying a rotary, mechanical, pulling force from above the path of said blanks and in an upward and rearward direction upon the under face of each said flap, and over an area of said under face progressively shifting inwardly longitudinally of the flap, while simultaneously holding down laterally removed portions of the body of the blank, until the flap and the portion of the blank to which it is articulated have been inclined upwardly out of the flat plane of the blank and then applying a rotary, mechanical, pushing force from above the path of said blanks and in a downward and forward direction upon the upper face of the main body of each said blank, just behind the said line of articulation to cause the flap to fold accurately on said line of articulation.
